Lacy & Lacy, Attorneys

UNITED STATES PATENT OFFICE.

MARTIN F. KETTLER, OF HOUSTON, TEXAS, ASSIGNOR TO MYSTIC WASHER COMPANY, OF HOUSTON, TEXAS, A CORPORATION OF TEXAS.

CLOTHES-WASHING APPARATUS.

Application filed January 27, 1926. Serial No. 84,178.

This invention relates to improvements in apparatus for washing clothes and has as its general object to provide an apparatus by the employment of which clothes may be readily, thoroughly and quickly washed without the expenditure of labor ordinarily involved in performing this task.

The washing apparatus embodying the invention is of that type in which boiling water is caused to circulate through the clothes to be washed, and another object of the invention is to so construct the apparatus as to provide for a more thorough circulation of the water than is effected by ordinary washing apparatuses of this class.

Another object of the invention is to so construct the apparatus that, in the operation thereof, fine streams of hot water will be directed onto the clothes arranged within the apparatus so as to effect a thorough cleaning of the clothes.

Another object of the invention is to provide novel means for so supporting the clothes to be washed that there will be no likelihood of scorching of the clothes in the event the water level in the apparatus is, through carelessness, permitted to become low.

Another object of the invention is to so construct the component parts of the apparatus that they may all be separated, thereby permitting of a thorough cleansing of the said parts to prevent the accumulation of dirt and rusting thereof, although the apparatus will preferably be formed of metal which will not rust.

Another object of the invention is to so construct the apparatus that the water therein will be boiled in a more or less confined space from which it will be discharged and circulate through the clothes within the apparatus, so that there will be a forceful circulation of the boiling water through the clothes and a more thorough cleansing of the clothes will be effected.

In the accompanying drawings:

Figure 1 is a vertical diametric sectional view through the apparatus embodying the invention.

Figure 2 is a horizontal sectional view taken substantially on the line 2-2 of Figure 1, looking in the direction indicated by the arrows.

Figure 3 is a fragmentary perspective

view of the delivery spout or head of the water column of the apparatus.

The apparatus embodying the invention comprises a container 1 which is preferably of gradually increasing diameter from its bottom to its top, the closed bottom of the container being indicated by the numeral 2 and the said container at its bottom being preferably of copper and interiorly tinned. The container 1 is provided with a removable cover 3 having a depending flange 4 to fit within the open top of the container and an outstanding flange 5 to rest upon the upper edge of the wall of the container, and a handle 6 of wood or other material of a more or less heat non-conducting character is secured centrally to the cover 3 by a bolt 7 and is spaced from the cover by a spacing sleeve 8 arranged upon the said bolt.

Arranged within the container 1 is the base 9 of a water trap which is indicated in general by the numeral 10, and this base is of shallow conical form and is provided at its lower edge with a rounded and downwardly extending circumferential flange 11 formed with a number of recesses which are indicated by the numeral 12, the said lower edge of the flange resting upon the bottom 2 of the container and the base 9 being of a diameter to substantially snugly fit within the lower end of the said container. The base 9 of the water trap is provided centrally with an upstanding upwardly tapered neck 13, and fitted and secured to the said neck is a vertically extending upwardly tapered water column or spout 14 extending centrally of the interior of the container and to a point somewhat above the open top thereof, the cover 3 of the container being of dome-like formation so as to accommodate the upper end of said column 14. At its upper end, the column 14 is provided with a sprayer head indicated in general by the numeral 15, and of inverted frusto-conical form, the circumferential wall of the said sprayer head being indicated by the numeral 16 and being formed with a number of small perforations indicated by the numeral 17. The top of the head is indicated by the numeral 18 and formed centrally with an inverted conical depression 19 the wall of which is concentric to the wall 16 of the said sprayer head. The said top 18 and its depression 19 are imperforate but

100
105

the perforations 17 extend throughout the entire area of the wall 16. The depression 19 constitutes a baffle which opposes the perforated wall 16 of the sprayer head and it 5 will be evident that the boiling water and steam generated within the trap 10 and rising through the column 14, will be forcibly discharged through the perforations 17 and sprayed outwardly and downwardly upon 10 the clothes which are arranged within the container 1 and about the said column 14.

In order that the water trap 10 may be retained in position resting upon the bottom of the container 1, it being understood 15 that the boiling water within the trap would somewhat tend to elevate the same, perpendicular ribs 20 are welded, soldered, or integrally formed upon the side of the wall of the container at suitably spaced intervals 20 about the lower portion thereof, and the peripheral portion of the base of the water trap is formed with notches 21 which are of dimensions to permit of the said base being fitted downwardly into the container with 25 the notches in registration with the ribs 20, until the trap has assumed a position resting at the lower edge of its flange 11 upon the upper side of the bottom 2 of the container, whereupon the said trap is rotated a short 30 distance so as to bring the notches 21 out of engagement with the said ribs 20, and at this time the lower ends of the ribs will substantially engage the upper side of the peripheral portion of the trap.

In order that the clothes to be washed 35 may be supported in position spaced from the base 9 of the water trap 10 and likewise sufficiently elevated above the bottom 2 of the container 1 to avoid any possibility of 40 scorching of the clothes should the water level be permitted to considerably lower through carelessness, a circular sheet metal false bottom 22 is arranged within the container with its periphery resting upon the 45 ends of the ribs 20 and with the wall of an opening 23 formed centrally therein, engaging about the neck 13 of the water trap. The perforations in this plate are indicated by the numeral 24 and are distributed over 50 the entire area of the plate.

A draw-off faucet or valve 25 is secured in the wall of the container at a point substantially intermediate the bottom 2 and the

false bottom 22, and constitutes a means whereby the container may be drained after 55 the clothes have been cleansed therein.

From the foregoing description of the invention it will be evident that water within the base 9 of the water trap 10 will be caused to boil when the apparatus is disposed above 60 a flame and that, being under pressure, due to expansion, will be caused to issue through the recesses 12 and flow upwardly through the perforations 24 in the false bottom 22 and through the clothes which are arranged within the container upon the said false bottom and about the column 14. Likewise, 65 boiling water will ascend within the column 14 and be forcibly delivered in fine streams through the perforations 17 in the sprayer head 15, which streams will be directed downwardly and outwardly upon the clothes to effect a thorough cleansing thereof. Likewise, it will be evident that a volume of steam will be generated which will be discharged through the said perforations, so 70 that the clothes will be subjected to the cleansing action of the steam as well as the hot water.

Having thus described the invention, what 80 I claim is:

A clothes washer comprising a container, a water trap in said container and including a substantially conical base having its peripheral portion resting upon the bottom 85 of the container and formed with inlets and its upper end formed with an upstanding outlet neck, a tubular column having its lower end fitted upon said neck, a sprayer head at the upper end of said column, inner 90 ribs formed vertically upon the lower portion of the walls of said container and spaced from its bottom, the peripheral portion of said base having recesses formed therein whereby the base may be moved downwardly 95 below the ribs and turned to dispose the ribs above portions of the base to lock the base in place, and a false bottom removably received in said container having its marginal portions resting upon the upper ends of said 100 ribs and its central portion formed with an opening snugly receiving said neck below the lower end of said column and resting upon the base.

In testimony whereof I affix my signature.
MARTIN F. KETTLER. [L. S.]
